UNITED STATES PATENT OFFICE.

JAMES N. STACY, OF PORTLAND, OREGON.

LETTER SEALING AND STAMPING MACHINE.

No. 852,003.

Specification of Letters Patent.

Patented April 30, 1907.

Application filed March 6, 1906. Serial No. 304,567.

To all whom it may concern:

Be it known that I, JAMES N. STACY, a citizen of the United States, residing at Portland, in the county of Multnomah and State 5 of Oregon, have invented certain new and useful Improvements in Letter Sealing and Stamping Machines, of which the following is a specification.

The present invention provides a machine 10 of the character and for the purpose specified, involving novel structural features and which may be used for sealing letters and applying postage stamps thereto, either separately or jointly, the machine embodying unique 15 moistening devices for wetting the sealing flap of the letter or package and the spot or place of said letter or package designed to receive the stamp; a stamp affixing and sealing arm of a shape to apply the pressure 20 where needed; feeding mechanism for the postage stamps and adjusting means therefor and stamp holding and regulating means.

For a full description of the invention and the merits thereof and also to acquire a 25 knowledge of the details of construction of the means for effecting the result, reference is to be had to the following description and accompanying drawings.

While the invention may be adapted to 30 different forms and conditions by changes in the structure and minor details without departing from the spirit or essential features thereof, still the preferred embodiment is shown in the accompanying drawings, in 35 which:

Figure 1 is a perspective view of a machine embodying the invention. Fig. 2 is a vertical longitudinal section thereof, the arm carrying the stamp moistener and the operating 40 frame being in full lines. Fig. 3 is a horizontal section of the machine on the line $w-w$ of Fig. 2. Fig. 4 is a longitudinal section of the lower portion of the head on the line $y-y$ of Fig. 3, showing the parts on a larger scale 45 and in the relation which they assume when the operating frame is raised. Fig. 5 is a view similar to Fig. 4 showing the relation of the parts when the operating frame is depressed. Fig. 6 is a transverse section on the 50 line $x-x$ of Fig. 2. Fig. 7 is a perspective view of the feed slide and feeder. Fig. 8 is a perspective view of the feeder. Fig. 9 is a perspective view of the feed regulator. Fig. 10 is a perspective view of the frame of 55 the flap moistener, the absorbent material and the cap plate being removed. Fig. 11 is

a front view of the head. Fig. 12 is a modification showing the invention adapted for both addressing and stamping letters or like packages. Fig. 13 is a detail view of the bed 60 plate provided with the stamp way showing more clearly the longitudinal slots through which the spurs of the feeder operate, the stamp way and feeder being indicated by dotted lines. Fig. 14 is a central longitudinal section of the stamp moistener on the line $z-z$ of Fig. 2. Fig. 15 is a detail perspective view of the horizontal or base portion of the head showing a modified form of feed regulator. Fig. 16 is a longitudinal section 70 of the portion illustrated in Fig. 15 showing the feeder about at the limit of its forward stroke.

Corresponding and like parts are referred to in the following description and indicated 75 in all the views of the drawings by the same reference characters.

The operating parts of the machine are mounted upon a suitable base 1 which may be of any construction or material. The 80 sealing and stamp affixing means are arranged intermediate of the ends of the base, whereas the moistening devices are located at one end of the base and the postage stamp roll at the opposite end thereof. The sealing 85 and postage stamp affixing means are mounted upon a head 2 which is of rectangular formation and comprises uprights 3 and 4 and horizontal members 5 and 6, the several parts being integrally formed or connected in any manner. An operating frame 7 of approximately U form is slidably mounted upon the head so as to receive a vertical reciprocating movement and is normally held elevated by means of a spring 85 which is located within the handle 9 into which telescopes a post 10 projected upward from the horizontal member 5 of the head. A horizontal rod 11 connects the lower ends 90 of the legs or side members of the operating frame 7 and passes through vertical slots 12 in the uprights 3 and 4 to materially assist the post 10 in directing the operating frame 7 in its reciprocating movements. The front leg or member of the operating frame 100 is provided at its lower end with a cutter 13 which is slightly inclined to the horizontal so as to operate by a shear action when severing the postage stamps from the strip. A plate 14 is fitted to the lower end of the front up-right 3 of the head and is formed with a slot 110 15 to admit of the foremost stamp having an

unobstructed passage from the stamp way formed in the bed plate. The portion of the plate bordering upon the lower side of the slot 15 is sharpened to form a cutting edge 5 which coöperates with the cutter 13 upon depressing the operating frame so as to sever the exposed stamp from the strip. A pressure head 16 is provided at the lower end of the front member of the operating frame 7 and overhangs the postage stamp so as to press the same upon the letter or package to be stamped. A pressure arm 17 extends laterally from the pressure head and preferably forms a part thereof and is deflected in its length to correspond approximately to the gummed edge of an envelop so as to centralize or apply the pressure directly in line with the gummed edge so as to insure a firm sealing thereof. The pressure head 20 and pressure arm may form a part of the operating frame or be secured thereto, as may be found most advantageous in construction of the machine.

The head 2 is secured in any manner to the bed plate 18, which in turn is fastened to the base 1. The stamp way 19 is formed in the bed plate or between said bed plate and a cap plate 20 fitted thereto. Longitudinal slots 21 intersect the stamp way and receive 30 the spurs 22 of the feeder 23 by means of which the stamp strip is unwound and moved through the stamp way upon depressing the operating frame 7. A slide 24 is mounted upon the bed plate and carries the feeder and is provided with openings 25 to receive the spurs 22. The slide 24 operates in an opening formed in the horizontal member 6 of the head 2 and is limited in its rearward movement by means of a stop 26 and keeper 27, 40 the latter spanning the slide and secured at its ends to the bed plate. The slide 24 is returned to a normal position by means of springs 28 which are arranged below the bed plate in a recess formed in the base 1 and which are connected at one end to the bed plate and at the opposite end to pendent ends 29 of a cross head provided at the inner or rear end of the slide 24 and which project through slots 30 formed in the bed plate upon 50 opposite sides of the stamp way.

The slide 24 is moved forward upon depressing the operating frame 7 by means of a feed pawl 31 which is pivotally connected to a block 32 adjustably mounted upon the horizontal rod 11 and secured thereon in an adjusted position by means of a set screw. The lower end of the feed pawl 31 enters a socket 33 provided upon the top side of the slide 24, said socket being closed at its sides 60 and front to prevent actual displacement of the feed pawl. The feed pawl normally inclines from the perpendicular, the angle being such as to insure a forward movement of the slide upon depressing the operating frame.

65 As the slide 24 bearing the feeder is moved

forward, the springs 28 are expanded and when the pressure is removed from the operating frame, the latter is returned to normal position by the spring 8 and the slide and feeder are returned to normal position by means of the spring 28. The feeder 23 consists of a spring which is attached at one end to the slide 24 and is free at its opposite end to have a vertical movement, said free end being provided with the spurs 22. The 70 feeder has a slot 34 which provides clearance for the socket 33 and for the lower portion of the feed pawl 31, thereby preventing interference of said parts with the free movements of the feeder. Extensions 35 project 80 laterally from the front end of the feeder 23 and serves in conjunction with other parts to control its movements. The front portion of the slide 24, as also the feeder 23, operate in the longitudinal space 36 of the 85 member 6, said space being of a width to snugly receive the slide so as to prevent any lateral play thereof. Flanges overhang longitudinal edge portions of the space 36 and serve to prevent vertical displacement 90 of the slide 24. These flanges may be provided in any manner and consist of edge portions of plates 37 which are secured to the upper side of the member 6 with their inner edge portions projecting over the space 36. 95 The lateral extensions 35 of the feeder engage under the flanges or inner projecting end portions of the plates 37 so as to hold the spurs 22 in engagement with the stamp strip when feeding the same. Opposite 100 notches 38 are formed in the inner edges of the plates 37 to admit of the lateral extensions 35 passing from above the plates or flanges 37 to a point below the same as the slide and feeder reach the limit of their rearward movement. The front portion of the flanges or inner projecting edge portions of the plates 37 is cut away to admit of the front end of the feeder moving upward the instant the extensions 35 clear the same, 110 thereby releasing the stamp strip and providing for a return of the feeder to normal position without effecting the stamp strip in any manner. As the slide is moved forward, the lateral extensions 35 travel beneath the flanges or inner projecting edge portions of the plates 37 and hold the spurs 22 in engagement with the stamp strip so as to draw the latter from the stamp roll and to project the stamp to be affixed beyond 115 the upright 3 of the head 2. When the stamp has reached a proper position to be cut from the strip the extensions 35 of the feeder are released and spring upward and upon the return of the slide and feeder to 120 normal position, the extensions 35 are above the flanges or the inner edge portion of the plates 37, and as the slide and feeder approach the limit of their return stroke, the extensions 35 are caused to move downward 125 130

through the notches 38 by means of springs 39 attached to the plates 37 and having their free ends deflected so as to enter the notches 38 to direct the extensions 35 therethrough. 5 Each spring 39 is flat and arranged in the plane of the plate 37 to which it is attached, the rear end of the spring being bent laterally, as shown at 40, and apertured to receive the fastening by means of which it is secured to 10 the plate. The springs 39 are of a tension to exceed the tension of the feeder 23 so as to overcome the same and cause its forward deflection to cause the extensions 35 to pass through the notches 38 so as to engage under 15 the flanges or inner edge portions of the plates 37 when the slide is next moved forward. Since the function of the springs 39 is to repress or return the feeder to normal position, they may be properly designated 20 as resetting means.

The means for regulating the effective stroke of the feeder consists of a frame 41 of approximately U form located at the outer or front end of the member 6 and having inner extensions 42 at the extremities of its side members which correspond with the flanges or inner edge portions of the plates 37 so as to engage over the extensions 35 of the feeder and hold the same in operative position 25 until said extensions 35 clear the extensions 42. A rod 43 is connected at one end to the frame 41 and passes through an opening in the upright 4 or other convenient portion of the head and which end is threaded to receive set nuts 44 by means of which the rod and frame 41 may be adjusted and secured in the required position. A trip 45 is attached to the cross piece of the frame 41 and inclines upward and forward, its lower end 30 extending into the path of the feeder so as to insure an upward movement thereof when reaching the limit of its forward stroke. The frame 41 constitutes in effect a regulator for the feeder and by adjustment thereof, the extensions 42 may be positioned so as to release the feeder at any point when nearing the limit of its forward stroke, whereby the stamp may be projected more or less so as to insure cutting of the same from the strip at 35 the proper point.

The stamp strip 46 is wound upon a screw 47, which in turn is mounted upon a pin 48 having its end portions notched in opposite side pieces of a spool holder 50 attached to 55 the outer or rear end of the bed plate 18. A cap 51 closes the spool holder and is hinged at one end to the rear portion thereof. A guard 52 is attached to the free end of the cap 51 and is adapted to close upon the bed 60 plate and cover the part thereof between the spool holder and the stamp way. An arm 53 projects laterally from the guard 52 and terminates in an eye which comes alongside of a companion eye applied to the base to 65 receive a padlock or other securing means

for locking the cap and guard when closed, thereby preventing anyone from appropriating postage stamps without operation of the machine. A brake is provided, and co-operates with the stamp strips to prevent the stamp moving too freely as by a rapid operation of the machine. The brake consists of a U shaped frame 54 embracing opposite sides of the spool holder and pivoted thereto, a light spring 55 connecting each arm of the frame 54 with the base of the spool holder or other convenient part of the machine. A roller 56 is mounted upon the cross bar connecting the arms of the frame 54 and confines the stamp strip between it and the bed 80 plate.

The stamp moistener is provided at the outer end of an arm 57 which is pivoted at its inner end to the base 1. The stamp moistener consists of a box 58 adapted to receive a quantity of water and having a pendent rim 59 forming a space in which is fitted an absorbent material 60, such as sponge, felt or the like. A valve controlled opening 61 is provided in the bottom of the box to admit 90 of water being supplied to the material 60. The stem of the valve is threaded in the upper portion of the box and is provided at its projecting end with a button 62 to be conveniently grasped when it is required to turn 95 the valve stem either to open or close the valve. A knob plug 63 closes an opening in the top side of the box through which water is supplied when it is required to charge the box. The knob provides convenient means 100 for operating the stamp moistener in the operation of the machine. The arm 57 is curved at its inner or rear end and passes through a slot in the upper end of a post or standard 64 attached to the base 1. A spring 65 normally presses the arm 57 upward so as to hold the box or stamp moistener elevated.

The moistener for the sealing flap of the letter or other package is rotated between the stamp moistener and the base and may 110 be of any length or width according to the size of the machine and is tapered to an edge at its inner end so as to readily enter the angular space formed between the sealing flap and the body of an envelop. The moistener 115 for the sealing flap of the envelop or other package is open upon its lower side and is hinged or pivoted to the base and is closed upon its top side to prevent wetting the body of the envelop or package. A spring 66 normally holds the envelop or package moistener in normal position, the latter being regulated by an adjustable stop 67 applied to the upper end of an arm 68 attached to the base 1. The spring 66 is attached to a pendant portion 69 of the envelop moistener and is located in an opening or recess of the base so as to be out of the way and protected from injury. An absorbent material, such as sponge, felt, cotton-waste or the like, is se- 130

cured within the frame or casing of the envelop moistener and serves to distribute the water and apply the same in proper quantity to the gummed portion of the sealing flap. 5 The envelop or package moistener in the preferred construction consists of an open frame 71 having inner flanges to support the absorbent material 70 and is closed at its top side by means of a plate 72. 10 A machine constructed substantially as herein set forth, when supplied with a roll of postage stamps and with a quantity of water in each of the moisteners, is in condition for operation. Inasmuch as the machine is specially adapted for sealing and stamping letters, the operation will be described in connection with such matter. The envelopes, after being filled, are placed upon the moistener 71, the body resting upon the plate 72, 15 whereas the sealing flap passes beneath the moistener with its gummed side adjacent to the absorbent material 70, the thin edge of the moistener entering the angular space formed between the body and sealing flap of 20 the envelop. When the envelop is properly adjusted, the sealing flap thereof comes between the base and envelop moistener and the body portion comes between the envelop moistener and the stamp moistener, and by 25 depressing the stamp moistener upon application of force to the knob 63, the envelop moistener is caused to turn upon its hinge or pivotal connection with the base, thereby moistening the gummed portion of the sealing flap and simultaneously wetting the upper right hand portion of the envelop designed to receive the stamp. The envelop is 30 now transferred from the moistening device to the stamp affixing and sealing devices, the 35 position of the envelop being properly determined by a shoulder 73 which forms a stop. After the envelop has been placed in position to receive the stamp, the operating frame 7 is depressed, thereby advancing the stamp strip a distance to bring the stamp to be 40 affixed in proper position and cutting the same from the strip and pressing it upon the moistened portion of the envelop, and at the same time the pressure arm 17 compresses 45 the envelop and insures a sealing thereof. Upon removing the pressure from the operating frame, the latter is returned to normal 50 position in the manner stated herein and the feeder is likewise reset by means of the operating springs. To materially assist in 55 fixing the position of the envelop upon the base, a clip 74 is provided and attached to the base and overhangs the shoulder and that part of the base designed to receive and support the envelop or package during the stamp affixing and sealing operation.

It is proposed in an adaptation of the invention to utilize the same for applying address strips to the packages or mailable matter simultaneously with the stamping and

sealing thereof. In such construction the spool holders and affixing devices are duplicated. In the event of the address strip being wider than the stamp strip the mechanisms co-operating therewith are proportionately enlarged, the construction and relative arrangement of the parts being substantially the same as that herein described. Inasmuch as the stamp and address occupy different relative positions upon the letter or package, the mechanisms are so disposed as to apply the stamp and address slip in the predetermined positions, hence the mechanism for applying the address slip is set in advance of the postage stamp applying mechanism. As shown in Fig. 12, the two operating frames are connected by means of a cross piece 75 to which a handle 76 is applied. Where the mechanisms are duplicated, the pressure arm 17 is dispensed with, since the pressure head 16 of the address applying mechanism takes its place. The plate 77 upon which the letter or package is placed to receive the address and postage stamp, is yieldable and underlaps the projecting portion of the address mechanism and is adapted to exert a pressure upon the sealing flap of the envelop sufficient to fasten the same. The moistener 78 for the address slip is connected to the stamp moistener in any manner and is set in advance of the stamp moistener to wet the envelop at about a central point so as to receive the address slip. The address, stamp and sealing machine, as disclosed in the adaptation in Fig. 12, is substantially the same as that herein described, the only difference being in duplicating the strip feeding and cutting mechanisms and the moistener for the address slip, as will be readily comprehended.

In the modification shown in Figs. 15 and 16, the feed regulator 41 is provided with notches 79 through which the lateral extensions 35 of the feeder 23 are adapted to pass when the stamp or address strip has reached the proper point in its travel to admit of the slip being cut off at the predetermined point. The forward edges of the notches 79 are beveled to form inclines 80 corresponding to the trip 45 and for a like purpose, namely, to insure the upward movement of the front portion of the feeder so as to effect disengagement thereof from the strip after the latter has been advanced the required distance. The notches 79 are of a length slightly less than the length of the lateral extensions 35 of the feeder and the forward ends of said extensions are upwardly deflected to enter the notches 79 and engage with and ride upon said inclines prior to the rear ends of said extensions clearing the rear edges of the notches 79, as indicated most clearly in Fig. 16. As a result of this construction and proportioning of the parts, the feeder has imparted thereto an upward pressure, which results in an in-

stantaneous upward movement of the feeder at the moment the rear edge of the extensions 35 clear the rear edge of the notches 79, with the result that a positive and quick release of the strip is effected. The provision of the inclines 80 and the upward deflection of the front portion of the feeder results in supplementing the inert spring action of the feeder tending to throw the same upward when released from the overlying and confining edges. The feed regulator 41 is adjustable and its position determines the relative location of the notches 79 and the consequent point of release of the strip, with the result that the feed of said strip may be regulated to a nicety. It is further noted that the inclines 80 are rigid in contradistinction to the corresponding part 45 previously referred to which is preferably yielding, being constructed of spring material.

Having thus described the invention, what is claimed as new is:

1. In a machine of the character specified, a tapered moistener adapted to enter the angular space formed between the sealing flap and body of the package and hinged at the edge remote from the tapered edge and having a pendent portion, a spring exerting pressure upon said pendent portion to hold the moistener in normal position, an arm, and an adjustable stop applied to said arm to limit the movement of the moistener in one direction.

2. In a machine of the character specified, a loosely mounted moistener for the sealing flap, and a second moistener for the postage stamp or address slip, the latter moistener being arranged above the sealing flap moistener and adapted to actuate the latter when itself operated.

3. In a machine of the character set forth, the combination of a pivotally mounted sealing flap moistener, and a second moistener located above the sealing flap moistener and adapted to actuate the latter upon application of pressure thereto.

4. In a machine of the character specified, the combination of an elongated sealing flap moistener inwardly tapered and having its lower side adapted to apply the moistening medium and its top side adapted to form a support for the package, said moistener being pivotally supported and spring actuated, a forwardly extended spring actuated pivoted arm, and a second moistener at the outer end thereof overhanging an end portion of the sealing flap moistener to actuate the latter when itself operated.

5. In a machine of the character specified, the combination of a sealing flap moistener pivotally supported and tapered inwardly from the pivoted edge, other moisteners arranged above the sealing flap moistener and carried by a common support, and adapted to dampen the envelop or package to cause

adhesion thereto of the stamp and address slips, slip feeding, cutting and affixing mechanisms, and a single handle for effecting simultaneous movement of said mechanisms.

6. In a machine of the character specified, the combination of a strip feeding mechanism, an operating frame for actuating said strip feeding mechanism, cutting mechanism actuated by the operating frame for severing the strip, a pressure head for applying the separated portion of the strip to the package, and a pressure arm for sealing the package simultaneously with the application of affixing the severed portion of the strip thereto, the cutting mechanism, the pressure head and the pressure arm being carried by the said operating frame.

7. In a machine of the character set forth, the combination of a slip feeding mechanism, an operating frame, a cutting mechanism for severing the strip and actuated by the operating frame, a pressure head, and a pressure arm extended from the pressure head and deflected in its length to conform to the deflected edge portion of the sealing flap so as to apply the force to the gummed edge portion thereof.

8. In a machine substantially as specified, the combination of a bed plate provided with a way or passage for the strip, a reciprocating feeder having spurs to engage with the strip to feed the same, said feeder having a lateral extension and normally tending to move away from the way or passage through which the strip is directed, means for holding the feeder repressed while advancing and in normal position, and other means for holding the feeder in engagement with the strip when nearing the limit of its forward stroke, and means for regulating the last mentioned and confining means to admit of regulating the feed of the strip.

9. In a machine of the character specified, the combination of a reciprocating feeder adapted to advance the strip, confining means for the feeder to hold the same in engagement with the strip and having cut away portions, an adjustable confining means for the feeder to admit of regulating the feed of the strip, means for disengaging the feeder from the strip when the latter has been advanced the required distance, and resetting means for returning the feeder to normal position when reaching the limit of its return stroke.

10. In a machine of the character set forth, the combination of a bed plate provided with a way or passage for a strip, a reciprocating feeder having a lateral extension, confining means for said feeder to hold the same in engagement with the strip when advancing and having cut-away portions, a flat spring secured at one end to the bed plate and having its opposite end deflected to enter a cut-away portion of said confining

- means for the feeder, and an adjustable feed regulator for holding the feeder in engagement with the strip for a greater or less distance of its forward movement.
- 5 11. In a machine of the character specified, the combination of a bed plate provided with a way or passage for a strip, a feeder having an extension, confining means overhanging the extension of the feeder and having a notch and a cut-away portion, spring resetting means secured at one end to the bed plate and extending about parallel therewith and having the opposite end projected into the notch of the feeder confining means, a feed regulator having an extension forming in effect a continuation of the feeder confining means, and means for disengaging the feeder from the strip when at the predetermined point of its forward stroke.
- 10 12. In a machine of the character specified, the combination of a bed plate provided with a strip way or passage, a spring actuated feeder having lateral extension, confining flanges upon opposite sides of the feeder to extend over the extensions thereof and having corresponding notches and cut away portions, horizontal springs secured at one end to the bed plate and having the opposite end bent and extended into said notches, a U shaped feed regulator having a centrally disposed trip extended into the path of the feeder, and means for adjusting the said feed regulator and holding it in an adjusted position.
- 15 13. In a machine of the character specified, the combination of a bed plate having a strip way or passage and having slots at opposite sides of said strip way, a slide having pendent portions at its rear end to extend through the slots of the bed plate, a spring having connection with the pendent portions of the slide to return and normally hold the latter in a given position, and a feeder connected with said slide and actuated thereby.
- 20 14. In a machine of the character set forth, the combination of strip cutting and feeding mechanisms, a holder for the strip roll, a brake member in contact with the strip, and a covering piece for the roll holder and brake member provided with an extension adapted to receive a lock device to prevent tampering with the parts.
- 25 15. In a machine of the character described and in combination with strip cutting and affixing mechanisms, a feeder, and means for confining the feeder and holding it in positive engagement with the strip for a definite length of its stroke, the same consisting of a plate having front and rear notches or cut away portions, the front notch having its forward edge beveled to provide an incline upon
- which the feeder is adapted to ride to insure and effect positive disengagement thereof from the strip.
- 30 16. In a machine of the character described, the combination with strip cutting and affixing mechanisms, of a feeder for the strip provided with a lateral extension, and means for holding the feeder to its work for a definite length of its stroke, said means consisting of a plate having front or rear notches or cut away portions, the front notch being of a less length than the length of the lateral extension of the feeder and having the forward edge beveled or inclined to engage with the front end of said lateral extension and deflecting the same upward through the notch, whereby instantaneous release of the feeder from the strip is effected.
- 35 17. In a machine of the character described, the combination of strip cutting and affixing mechanisms, a feeder provided with a lateral extension having its front end upwardly deflected, and a feed regulator consisting of a plate having a notch, the forward edge of which is beveled to provide an incline to engage with the deflected end of the feeder extension to cause the same to move upward and effect a quick release of the strip when the latter has reached the required advancement.
- 40 18. In a machine of the character described, the combination of strip cutting and affixing mechanisms, a feeder for the strip having a lateral extension, the front end of which is upwardly deflected, and an adjustable feed regulator comprising a plate having a notch of a less length than the length of the feeder extension and having the front edge of said notch upwardly beveled to provide an incline to engage with the deflected end of the feeder extension to effect instantaneous release of the strip.
- 45 19. In combination, strip cutting and affixing mechanisms, a reciprocating feeder having opposite lateral extensions, side plates having notches for said lateral extensions to pass through, means for compelling the extensions of the feeder to pass downward through said notches, a plate having opposite notches for the lateral extensions of the feeder to pass upward through and having the front edge of the notches beveled to form inclines, and means for adjusting and securing said plate in the required adjusted position.
- 50 In testimony whereof I affix my signature in presence of two witnesses.
